[57] **CLAIM**

The ornamental design for a double-barrel gas torch, substantially as shown.

DESCRIPTION

FIG. 1 is a perspective view of a double-barrel gas torch showing my new design, together with a broken-line representation of a pressure regulator providing the mounting therefor;

FIG. 2 is a front elevational view thereof;

FIG. 3 is a top plan view thereof;

FIG. 4 is a bottom plan view thereof;

FIG. 5 is a rear elevational view thereof;

FIG. 6 is a side elevational view thereof, looking toward the right side thereof; and

FIG. 7 is a side elevational view thereof, looking toward the left side thereof.

FIG.1

FIG. 2

FIG. 3

FIG. 4

FIG. 5

FIG. 6

FIG. 7
